Atty. Attorney S.

UNITED STATES PATENT OFFICE.

WILLIAM L. MANTHA, OF BAYPORT, NEW YORK.

APPARATUS FOR TRUING HUB-FLANGE SEATS.

Application filed May 2, 1922. Serial No. 558,036.

To all whom it may concern:

Be it known that I, WILLIAM L. MANTHA, a citizen of the United States, residing at Bayport, in the county of Suffolk and State

of New York, have invented certain new and useful Improvements in Apparatus for Truing Hub-Flange Seats, of which the following is a specification, reference being had therein to the accompanying drawings.

10 This invention relates to an apparatus for truing hub flange seats, and the object of the invention is the construction of a simple and efficient apparatus for truing the hub flange seat of an automobile wheel.

15 My apparatus can be operated by hand or power; it feeds automatically across the face of the wheel leaving the face true with the outer rim.

With the foregoing and other objects in view, my invention comprises certain novel combinations, constructions and arrangements of parts as will be hereinafter described, illustrated in the accompanying drawings, and more particularly pointed 25 out in the appended claims.

In the drawings:

Figure 1 is a top plan view of an apparatus constructed in accordance with the present invention, while

30 Figure 2 is a view in side elevation of the same.

Figure 3 is a top plan view of the supporting frame.

Figure 4 is an enlarged, fragmentary view, partly in section and partly in side elevation, of the gauge device.

Figure 5 is a sectional view, taken on line 5—5, Fig. 1.

Figure 6 is a sectional view, taken on line 6—6, Fig. 4, and looking in the direction of the arrows.

Figure 7 is a sectional view, taken on line 7—7, Fig. 4, and looking in the direction of the arrows.

45 Figure 8 is a perspective view of the sleeve.

Referring to the drawings by numerals, 1 designates the supporting frame which comprises a body 2, from which extend integral arms 3. Formed upon each arm 3 is a depending lug 4 forming a supporting foot. Slidably mounted on each arm 3 is a substantially rectangular bracket 5, which bracket 5 has a head 6. Threaded into head 6 is a screw 7. The rim 8 of wheel 9 is placed upon the supporting frame, then

the screws 7 are screwed against the outer face of the rim tightly clamping the rim 8 upon the arm 3 of the supporting frame, Figs. 1 and 5.

50 A spindle 10 extends through the body 2, the extreme lower end of the spindle being threaded into nut 11; the spindle is provided with a hub portion 12 that rests, at its lower end, upon body 2, and on the spindle 10 and immediately above, and in engagement with hub portion 12, is sleeve 13. The sleeve 13 is provided with a notch 14 that straddles spur plate 15. Spur plate 15 is provided with a spur 16 that engages the 70 outer face of sleeve 13. Sleeve 13 is provided with a spur 17 that is adapted to be engaged by the star wheel 18 secured to the inner end of gauge screw 19.

75 The gauging device 20 is revolvably mounted upon spindle 10 and includes hollow body 21, which body 21 is provided with a detachable handle 22 that is held upon the body by screw 23. Handle 22 is provided with a grip 24. A shaft 25 has its inner end integral with the hollow body 21, and its outer end engages the lower end of angle brace 26. A screw 27 extends through brace 26 into shaft 25 holding the brace securely to the outer end of the shaft. 80 The upper end of brace 26 is secured to the hollow body 21, at 27^a, Fig. 2. The extreme lower end of brace 26 projects below shaft 25, and gauge screw 19 is revolvably mounted on the brace; its inner end 28 projects a slight distance into the hollow body 21, with the star wheel 18 bearing against the hollow body 21.

85 A marker device 29 is provided, comprising body 30 slidably mounted on shaft 25, with screw 19 extending therethrough (Fig. 6) so that when the operator rotates screw 19, the body 30 will be adjusted longitudinally of shaft 25. A marker pin 31, which has its lower end sharpened and constitutes a cutter is slidably mounted in a vertical plane upon body 30 and is held in an adjusted position by screw 32.

100 When this device is in use the wheel which has become warped has its hub removed and the wheel is then put in place as shown in Figures 1 and 2, the rim being clamped tightly against the arms 3 by the set screws 7. The sleeve 21 will now be placed upon the stem or spindle 10 and the shaft 25 and screw 19 will extend radially above the contacting inner end portions of the spokes.

One or more of the sleeves 13 will of course, be put in place if necessary and the cutter 29 adjusted so that as it moves along the shaft 25 the contacting portions of the 5 spokes will be trimmed in the same manner that a lathe would operate. In order to perform the cutting the sleeve is rotated by means of the handle 22 and as it rotates the star wheel 18 will strike the finger 17 thus 10 causing the screw to be rotated and the carrier 30 moved outwardly along the shaft. After one complete cut has been made the carrier will be returned to its original position near the sleeve, the cutter lowered and 15 the operation repeated until the warped portion is entirely cut away. After the proper amount of cutting has been performed the sleeve will be lifted from the spindle and the screws 7 loosened so that the wheel 20 can be removed and the hub put back in place. The hub will now fit properly and the wheel will be true. If it is only desired to test the wheel to see if it is true the pin would not be initially set low enough to 25 make a cut and the device would then serve only as a gauge with the pin as a gauge pin to indicate if cutting is necessary.

My apparatus is especially built for the purpose of truing up a center circle, on an 30 automobile wheel. This apparatus will eliminate wear on tires, allow the driver to keep his car in perfect alinement. The device is so simple it can be installed in the smallest repair shops. Heretofore, one had 35 to lay up his automobile, and remove the

warped wheel, ship it to the nearest city to have it trued up in a lathe. This apparatus eliminates all that time and expense.

What I claim is:

1. In an apparatus of the class described, 40 the combination with a frame, of a spindle extending axially of said frame and provided near its lower end with a hub portion resting upon said frame, said spindle provided with a portion extending through 45 said frame, a spur plate attached to said hub portion, a sleeve provided with a spur resting on said hub portion and engaging said spur plate, a hollow body on said spindle and engaging said sleeve, said hollow 50 body provided with an operating device including an adjusting screw having a spur wheel, and said spur wheel adapted to engage the spur of said sleeve.

2. In an apparatus of the class described, 55 a wheel support, a spindle extending from said wheel support, a sleeve fitting upon said spindle and held against rotation, a spur extending from said sleeve, a hollow body rotatable upon said spindle and resting upon said sleeve, and operating means carried by said body and provided with an adjusting screw having a spur wheel adapted to be engaged by the spur of said sleeve and turned thereby as the body is rotated 60 upon said spindle.

In testimony whereof I hereunto affix my signature.

WILLIAM L. MANTHA.
